COLLAPSIBLE ENEMA BAG OR SIMILAR ARTICLE

Richard E. Ericson, Keene, N.H., assignor to Elliot
Laboratories, Inc., Fitzwilliam, N.H., a corpora-
tion of New Hampshire

Filed July 24, 1969, Ser. No. 18,387

Term of patent 14 years

Int. Cl. D24—02

U.S. Cl. D83—1

FIG. 1

FIG. 2

FIG. 3

FIG. 4

FIG. 7

FIG. 5

FIG. 6

FIG. 1 is a front view in elevation of a collapsible enema bag or similar article with the foldable spout unfolded showing my new design.

FIG. 2 is a rear view in elevation thereof.

FIG. 3 is a right side view in elevation.

FIG. 4 is a left side view in elevation.

FIG. 5 is a bottom plan view.

FIG. 6 is a top plan view.

FIG. 7 is a left side view in elevation like FIG. 4 but with the foldable spout folded.

I claim:

The ornamental design for a collapsible enema bag or similar article, substantially as shown and described.
